PULSE-ACTUATED STRIP LINE FERRITE CIRCULATOR SWITCH UTILIZING RESIDUAL MAGNETIZATION TO ELIMINATE HOLDING CURRENT

Leo Freiberg, San Jose, Calif., assignor to Lockheed Aircraft Corporation, Burbank, Calif.
Filed Apr. 30, 1962, Ser. No. 191,358
2 Claims. (Cl. 333—1.1)

The present invention relates to a circulator switch and more particularly to a pulse-actuated circulator switch which eliminates the necessity of holding current and provides minimum magnetic reluctance.

One of the major disadvantages of employing a circulator as a microwave switch has been the requirement of holding current to maintain the circulator in the switched position. That is, prior circulators have required the use of continuous current through an electromagnet to maintain switching in a predetermined mode. To reverse the switching mode or the direction of circulation, the current is reversed through the electromagnet. Again, however, it is necessary to maintain continuous current in this reversed direction to maintain this reversed switching mode. The primary disadvantage of this technique is the large amount of power consumed due to the continuous current requirement. This becomes especially critical in space applications where operation may be required over several months or years and only a small amount of power is available.

The present invention obviates this disadvantage by employing a switchable magnetic material which magnetizes upon the application of a current pulse in one direction and retains this direction of magnetization after the pulse has been removed. Opposite polarity or switching mode is obtained by applying a current pulse of opposite polarity. In this manner the only power required is during the switching interval when the pulse is being applied thereby obviating the large power consumption of holding current.

After this switching pulse has been removed, the switch will theoretically remain indefinitely in the selected mode and in actual practice it has never been found necessary to reapply a pulse to maintain the switch in the selected mode.

This has been accomplished by the unique utilization of a material having a coercive force such that the magnetization may be reversed with a current pulse of reasonable magnitude and still have the proper amount of retentivity at the termination of the current pulse. In addition, the present invention provides a closed loop magnetic path that provides minimum magnetic reluctance thereby resulting in minimum current or power requirement as well as making it possible to operate at a higher frequency for a given current pulse.

Accordingly, an object of the present invention is to provide a low power consuming circulator switch.

Another object of the present invention is to provide a pulse-actuated circulator switch which eliminates the necessity of holding current.

A further object of the present invention is to provide a circulator switch which will indefinitely remain in a selected switched position without re-pulsing or using a holding current.

A still further object of the present invention is to provide a pulse actuated circulator switch employing a material having a coercive force such that the magnetization may be reversed with a current pulse of reasonable magnitude and still have the proper amount of retentivity at the termination of the current pulse.

A still further object of the present invention is to pro-

vide a pulse actuated ferrite switch having a closed loop magnetic path that provides minimum magnetic reluctance thereby resulting in minimum current or power requirement as well as making it possible to operate at a higher frequency for a given current pulse.

The specific nature of the invention, as well as other objects, uses and advantages thereof, will clearly appear from the following description and from the accompanying drawing in which:

10 FIGURE 1 is a top elevation, partly in section, of the pulse actuated circulator switch of the present invention.

FIGURE 2 is a side elevation of the circulator switch shown in FIGURE 1.

15 FIGURE 3 is a sectional view of the circulator switch shown in FIGURE 1.

FIGURES 4A and 4B are illustrations of the strip-line member of the circulator switch shown in FIGURES 1 through 3 and depicts the switching action during the two modes of operation.

20 FIGURE 5 is a diagram illustrating the B-H characteristic of the electromagnetic core material during different conditions of operation.

FIGURE 6 is a diagram illustrating the interrelation of the applied input pulses and the microwave switching in 25 the to output legs of the circulator switch.

FIGURE 7 is a family of curves illustrating isolation or power leakage into the non-switched arm.

FIGURE 8 is a family of curves illustrating insertion loss or the sum of the reflected and internally consumed 30 power.

FIGURE 9 is a family of curves illustrating the VSWR (voltage standing wave ratio) or the energy reflected back into the input leg.

Like numerals designate like elements throughout the 35 figures of the drawing.

In FIGURES 1 and 2 are illustrated the pulse actuated circulator switch 11 of the present invention. Switch 11 includes top plate 13 and bottom plate 15 both of which have concentric openings formed therein for receipt of cores 17 and 19, respectively. Preferably the diameters of the openings in plates 13 and 15 and the diameters of cores 17 and 19 are selected for press fitting thereby eliminating the necessity of mechanical or adhesive interconnections. Plates 13 and 15 are connected to annular side member 21 by means of screws 23 or the like resulting in the formation of cylindrical cavity 24 formed between the interior surfaces thereof.

Cores 17 and 19 are wound by wire 25 and in the same direction such that opposite polarity of the adjacent faces 50 results upon the application of a current pulse having a predetermined polarity as generally depicted in FIGURE 3. The outer faces of cores 17 and 19 are series connected by means of U-shaped bracket 27 to provide a closed magnetic loop the function of which will hereinafter become apparent. Bracket 27 is preferably made of material having a low reluctance, such as soft iron.

Disposed within cylindrical cavity 24 is strip-line member 29 having conductor legs 31a, 31b and 31c and junction 33 of the shape substantially as shown. The 60 ends of these conductor legs are connected to terminal pins 35 of connector plugs 37 as by means of solder or the like. It will be particularly noted that strip line member 29 is made of soft iron which is then thinly coated with a material having high conductivity such as silver. 65 The thickness of the coating is of the order of about .0005 inch. As will hereinafter become apparent, it is critical that the base material be made of soft iron or the like since it provides a low reluctance and it is critical that the soft iron, which has poor microwave transmitting characteristics, be coated with silver or the like since silver has high microwave transmitting characteristics which is essential for strip-line transmission in the fre-

quency range of about 200 megacycles to about 10,000 megacycles.

Cylindrical members 41 and 42 are concentrically disposed in cavity 24 and spaced apart by strip line member 29. The opposite end surfaces of member 41 are respectively in facial contact with the inner surface of core 17 and the upper surface of strip line member 29. The opposite end surfaces of member 42 are respectively in facial contact with the inner surface of core 19 and the lower surface of strip line member 29. Although the reluctance of the magnetic path is somewhat increased, the end surfaces of members 41 and 42 are connected to the opposite surfaces of strip line member 29 by an extremely thin adhesive such as epoxy resin having mixed therewith a material having a low reluctance. An adhesive is generally not necessary to connect the inner surfaces of core 17 and 19 to members 41 and 42 since, upon assembly, intimate surface contact may be realized by simultaneous force fitting cores 17 and 19.

The magnetic characteristics of cores 17 and 19 are critical features of the present invention. It has been found that it is possible to obtain continuous switching by the application of a short time duration pulse to lead wires 25 by means of current pulse device 45 provided the material from which cores 17 and 19 are made have the necessary magnetic characteristics. It has been found that SAE 4130 steel has the necessary retentivity as well as coercive force characteristics. The coercive force of the magnetic material must be such that the retentivity, or remanent magnetization, may be reversed with a current pulse of reasonable magnitude and still have the proper amount of retentivity at the termination of the current pulse. The required switching current pulse depends upon the closed loop circuit reluctance which is highly dependent upon the materials forming the closed loop circuit.

It is necessary to form members 41 and 42 from ferrite material in order to obtain circulator or switching action. The symmetrical junction, in the absence of the biased ferrite material, normally divides incoming high frequency energy equally between the remaining two arms. However, when magnetically biased ferrite material is added to the junction, high frequency energy entering any terminal is all directed to the adjacent terminal, the selected terminal being determined by the direction of the magnetic biasing field. During switching, the ferrite material has a low reluctance and after it has become switched or saturated, the reluctance becomes relatively large. However, since the reluctance is low during switching, the power or current required for switching is not excessive.

Operation

The operation of the present invention will be described in conjunction with FIGURES 3 through 6. In FIGURE 3 is illustrated a cross-sectional view of the switch wherein arrows 47 denote the direction and configuration of the lines of force created upon the application of a positive pulse to windings 25 from current pulse device 45. This same direction and configuration of flux lines will exist upon termination of the current pulse since cores 17 and 19 will possess a predetermined amount of retentivity as will hereinafter be explained with relation to FIGURE 5. Upon the application of a negative current pulse, the configuration of the lines of force will remain the same; however, the direction will be reversed.

It will be noted that the diameter of members 17 and 19 is large compared to the effective diameter of junction 33. This relationship is highly desirable since the lines of force would otherwise enter strip line member 29 at an angle other than 90° resulting in an undesirable non-uniform field at junction 33.

FIGURE 4A depicts the switching direction of the microwave energy upon the application of a positive pulse wherein the small circles indicate the field is leaving the plane of the paper. FIGURE 4B depicts the switching direction of the microwave energy upon the application

of a negative pulse wherein the crosses indicate the field is entering the plane of the paper.

In order to more fully appreciate the unique features of the present invention, it is believed the following analysis is pertinent: It should be initially pointed out that the operating frequency of the above-described circulator switch is a function of several parameters which include (1) diameter of the ferrite, (2) type of ferrite material, (3) thickness of the ferrite, (4) width of strip line member, (5) configuration of junction 33 and (6) retentivity or biasing gauss. The latter parameter (6) is perhaps the most critical inasmuch as the realization of sufficiently high frequency of operation is highly dependent upon adequate biasing gauss.

The retentivity may be determined from the relationship:

$$\phi = \frac{MMF}{R}$$

where ϕ is the total flux passing through core material 17 or 19, MMF is the magnetomotive force in oersteds H (where $H=KNI$ where K is a constant and NI is the ampere turns of windings 25) and R is the reluctance. Knowing the total flux, the retentivity biasing gauss B may be readily determined from the relation

$$B = \frac{\phi}{A}$$

where A is the area of the core material.

FIGURE 5 includes a family of curves denoted as "I" and "II" illustrating the B-H characteristics of core 17 and 19 during different conditions of operations. As previously explained, for minimum power and maximum frequency, it is desirable to have maximum retentivity. With a given pulse current, curve "I" will be the characteristic curve when the closed loop magnetic reluctance is a predetermined amount and curve "II" will result when the closed loop magnetic reluctance is larger than this predetermined amount. It can therefore be seen that maximum retentivity is obtained with minimum reluctance and this is realized by the present invention as previously explained. It will be noted that upon removal of the current pulse, the operating point on the B-H loop will be at some position between points "a" and "b." If the reluctance is low, the operating point may be at point "c," whereas, if the reluctance is high, the operating point may be at point "d." It can therefore be seen that it is desirable to have minimum reluctance.

To reverse the field direction, a pulse of opposite polarity is applied which changes the operating point to point "f" and upon termination of the pulse the operating point will reside at some position, depending upon the reluctance, between points "g" and "h."

In FIGURE 6 is illustrated an actual reproduction of an oscilloscope trace showing the pulse actuated switching action of the present invention. FIGURE 6A depicts sequential positive and negative current pulses applied to windings 25 from current pulse device 45. The microwave output from legs 31b and 31c is shown in FIGURE 6B and FIGURE 6C, respectively. These traces were obtained by the use of five ampere current pulses which are sufficient to reverse the magnetization and obtain a magnetic field retentivity of 200 gauss. Pulse widths of 140 milliseconds were used; however, since the switching time of the core material is about five milliseconds, pulse widths of ten milliseconds are sufficient. Faster switching times may be obtained by reducing the number of turns about cores 17 and 19.

FIGURES 7, 8 and 9 illustrate the characteristics of the circulator switch biased only by the remanent magnetization of cores 17 and 19. FIGURE 7 is a family of curves illustrating isolation or power leakage into the non-switched arm, FIGURE 8 is a family of curves illustrating insertion loss or the sum of the reflected and internally consumed power and FIGURE 9 is a family of

curves illustrating the VSWR (voltage standing wave ratio) or the energy reflected back into the input leg. The operating condition of each of the curves of FIGURES 7 through 9 is self explanatory from the symbols and corresponding legends affixed thereto.

It is to be understood in connection with this invention that the embodiment shown is only exemplary, and that various modifications can be made in construction and arrangement within the scope of the invention as defined in the appended claims. For example, this circular switch may be employed over the entire microwave spectrum and various dimensions and configurations of elements will be employed depending upon the selected frequency of operation. Similarly, the dimensions and configurations of elements may be changed at a predetermined frequency and still remain within the scope of the present invention. In addition, it will be obvious to one skilled in the art that the above described biasing technique may be used in conjunction with a Faraday rotation circulator or a differential phase shift circulator to provide a circulator switch.

What is claimed is:

1. A microwave switch comprising means forming a cavity, an input communicating with said cavity, first and second outputs communicating with said cavity, a member disposed in said cavity and having first, second and third legs connected to a common junction, the other ends of said first, second and third legs respectively connected to said input and first and second outputs, first and second members operatively connected to said means and located on opposite sides of said common junction, ferrite material in facial contact with said first member and one side of said junction, ferrite material in facial contact with said second member and the other side of said junction, said first and second members consisting of switchable magnetic SAE 4130 steel which retains residual magnetization upon being switched, windings disposed about said first and second members, means operatively connected to said windings for applying positive and negative current pulses, whereby after the application of a positive current pulse said first and second members retain residual magnetization and provide a field in a first direction through said junction resulting in the transmission of a microwave signal from said input to said first output and after the application of a negative current pulse said first and second members retain residual magnetization and provide

a field in a direction opposite to said first direction through said junction resulting in the transmission of a microwave signal from said input to said second output.

2. A microwave switch comprising means forming a cavity, an input communicating with said cavity, first and second outputs communicating with said cavity, a member disposed in said cavity and having first, second and third legs connected to a common junction, said member being formed of a material having a low reluctance and coated with a material having high conductivity, the other ends of said first, second and third legs respectively connected to said input and first and second outputs, first and second members operatively connected to said means and located on opposite sides of said common junction, ferrite material in facial contact with said first member and one side of said junction, ferrite material in facial contact with said second member and the other side of said junction, said first and second members consisting of switchable magnetic SAE 4130 steel which retains residual magnetization upon being switched, windings disposed about said first and second members, means operatively connected to said windings for applying positive and negative current pulses, means interconnecting said first and second members made of a material having a low reluctance, whereby after the application of a positive current pulse said first and second members retain residual magnetization and provide a field in a first direction through said junction resulting in the transmission of a microwave signal from said input to said first output and after the application of a negative current pulse said first and second members retain residual magnetization and provide a field in a direction opposite to said first direction through said junction resulting in the transmission of a microwave signal from said input to said second output.
